UNITED STATES PATENT OFFICE.

FRANK RHIND, OF BRIDGEPORT, CONNECTICUT, ASSIGNOR OF ONE-HALF TO THE BRIDGEPORT BRASS COMPANY, OF SAME PLACE.

DESIGN FOR A TIRE-SCRAPER.

SPECIFICATION forming part of Design No. 30,036, dated January 17, 1899.

Application filed June 28, 1898. Serial No. 684,698. Term of patent 14 years.

To all whom it may concern:

Be it known that I, FRANK RHIND, a citizen of the United States, residing at Bridgeport, Fairfield county, Connecticut, have invented a new and original Design for a Tire-Scraper, of which the following is a specification.

The accompanying drawing is a perspective view of a tire-scraper showing my design.

The leading or characteristic feature of my design comprises a tire-scraper in the form of a flat plate of rectangular form having three of its sides formed with substantially semicircular recesses.

In the drawing, 1 is a generally rectangular plate having in three of its sides substantially semicircular recesses 2. At the fourth side of the plate is a projection.

What I claim is—

The design for a tire-scraper herein described and shown.

FRANK RHIND.
